UNITED STATES PATENT OFFICE.

JOSEPH LOUIS KIEFFER, OF MONTREAL, CANADA.

WORK-GAGE FOR SHOE-SEWING MACHINES.

SPECIFICATION forming part of Letters Patent No. 729,605, dated June 2, 1903.

Original application filed May 1, 1902, Serial No. 105,493. Divided and this application filed October 20, 1902. Serial No. 127,968. (No model.)

To all whom it may concern:

Be it known that I, JOSEPH LOUIS KIEFFER, a subject of the King of Great Britain, residing at the city of Montreal, district of Montreal, Province of Quebec, Canada, have invented certain new and useful Improvements in Work-Gages for Shoe-Sewing Machines; and I do hereby declare that the following is a full, clear, and exact description of the invention, such as will enable others skilled in the art to which it appertains to make and use the same.

My invention relates to improvements in shoe-sewing machinery of that class known technically as the "outsole-stitcher"—that is to say, a machine adapted to sew the sole of the shoe to the welt thereof and to form a lock-stitch by means of two interlocking threads, which are looped together in the well-known manner of sewing-machines.

The principal object in view of the invention herein described is to improve the adjustment of the work-gage on this class of machinery which is adapted to regulate the distance of the seam from the edge of the work. This gage in the present type of machine is caused to be pushed backward and forward from and toward the awl by means of a handle mounted on the reciprocating carriage and caused to partake of the reciprocative movement of the latter. This adjustment in the present type of machine is rendered difficult by reason of this latter fact during the time that the machine is in motion, because a rapidly-reciprocating handle cannot be grasped and operated to adjust the work-gage satisfactorily, but it is necessary to stop the machine entirely in order to properly adjust the gage. It is therefore my object in the present invention to provide a stationary handle which is so connected to the work-gage as to adjust the position of the same, although the work-gage is mounted upon and reciprocates with the carriage as heretofore.

This mechanism constitutes a part of the machine described and claimed as a whole in my former application for a patent, Serial No. 105,493, filed May 1, 1902, of which this application is a division.

The mechanism constituting my invention

consists in a rock-shaft mounted to oscillate in a stationary block, the direction of the shaft being parallel with the direction of motion of the carriage, whose lower end carries the work-gage, and the said rock-shaft carries at its end adjacent to the work-head a gear-segment which engages with a small segmental pinion geared to and reciprocating with the carriage, so that the said pinion may be moved backwardly and forwardly with the carriage without interfering with its intermeshing connection with the gear-segment carried by the said rock-shaft. Thus the adjusting means of the work-gage is perfectly stationary and may be set to as great a nicety as may be desired by means of a tangent screw abutting against a boss on the hub of an adjusting-arm carried by the shaft without stopping or in any way interfering with the operation of the machine.

I have illustrated my improved work-gage mechanism apart from the mechanism of the machine as a whole in the accompanying drawings, wherein—

Figure 1 is a perspective view of the operating parts of my improved work-gage adjustment *in situ*, the stationary parts of the carriage in which they are mounted being indicated in dotted lines. Fig. 2 is a perspective view showing the parts of the work-gage and adjusting device mounted on the adjusting-shaft, these parts being shown in separated positions. Fig. 3 is a perspective view of the block in which the work-adjusting shaft is mounted to turn. Fig. 4 is a perspective view of the work-gage from the rear left-hand side thereof. Fig. 5 is a perspective view of the tangent stop-screw adapted to regulate the movements of the shaft of the work-gage-adjusting mechanism. Fig. 6 is a perspective view of the work-gage pinion and its shaft. Fig. 7 is a perspective view of the feed-carriage, showing the work-gage, presser-foot, slotted guide-block, and other correlated parts thereof in position thereon. Fig. 8 is a similar view showing the feed-carriage by itself.

The same numerals of reference denote like parts in all the figures of the drawings.

The work-gage itself is adjustably mounted upon the carriage of the machine, which is shown in Figs. 7 and 8 and designated 9. This carriage has a depending leg 10, which

extends between the two standards of the work-head of the machine, and the horizontal portion is arranged to slide in a guide-channel formed in the work-head, as fully described in my former application. The construction of the feed-carriage and the parts appended thereto not connected to the work-gage need not be here described at length, but may be briefly referred to.

10 11 designates the presser-foot lever, which is pivoted on the carriage by the pin 12, and 13 designates the presser-foot bar, which, as shown, slides in a nearly vertical groove 14 in the front edge of the limb 10 of the feed-carriage and is connected with the feed-lever by the swivel-joint 15. At 16 is shown the presser-foot, which is adapted to coöperate with the table in holding the work during the stitching operation, and feeding the same 15 along with each advance movement of the carriage. The parts mounted on the carriage, which are shown in Fig. 7, relate to the stitch-adjusting mechanism and need not be here referred to, as they form no part of my present invention.

Near the lower end of the leg 10 of the feed-carriage and at its inner or left-hand side is formed a rectangular groove 17, which is destined to receive the work-gage 18. (Shown in 20 detail perspective in Figs. 1 and 4 and mounted in position also in Fig. 7.) This is in the form of a short rectangular plate having rack-teeth 19 formed on its upper surface and a rectangular bent finger 20, which forms the 25 gage and coöperates with the presser-foot 16 and the work-table in striking against the edge of the work and regulating the distance between the edge and the seam. The gage-plate 18 has also a longitudinal slot 21 formed 30 therein through which passes the pivot-pin of the awl-block, which is also mounted on the carriage and partakes of the vibratory movement thereof, but is not herein shown, as it forms no part of my present invention.

40 45 The work-gage motion is shown in general perspective in Fig. 1, and it differs from all preceding motions in having a stationary adjusting-handle 22, which is bent at right angles, as shown at 23, and the end is provided 50 with a hub 24, connected by a set-screw 25 to the adjusting-shaft 26, which is pivotally mounted in a stationary block 27, (shown in detail perspective in Fig. 3,) which is secured to the lower side of that part of the work-head 55 of the machine which supports and forms the guideway for the carriage and which is shown in dotted lines in Fig. 1 and designated 28. The block 27 is secured to the work-head by means of screw-bolts or other like 60 fastenings passing through vertical apertures 29. The shaft 26 is mounted in a transverse horizontal aperture 30 in the block 27, and this aperture 30 is connected with the exterior of the block by a cut 31, the object of 65 this cut being to divide the block, so as to enable one of the screws securing it to the work-head to tighten it to the requisite extent

to produce a certain amount of friction upon the shaft 26 to prevent its being accidentally moved or by the reaction of the pressure upon the work-gage and otherwise except when it is positively moved by the handle 22. The shaft 26 extends inwardly to a point opposite the end of the overhanging portion 28 of the work-head, and upon this end is mounted a gear-segment 32, which has an aperture 33 passing over the stud 34 on the end of the shaft, to which it is keyed by means of pins 35, seated in notches 36 in the interior face of the aperture 33 and the segment 32 and is prevented from coming off the shaft by a nut 37 on the screw-stud 38, these parts being shown in detail in Fig. 2. The gear-segment 32 is arranged to mesh with a gear-pinion 39, which is mounted upon a short counter-shaft 40, carried in an aperture 41 in the depending leg 10 of the carriage, and the gear-pinion 39, as herein shown, is clamped in position on the shaft 40 by clamping-ears 42 and a screw 43. The other end of the shaft 40 is provided with a pinion 44, which is on the opposite face of the leg 10 of the feed-carriage and is set in a circular recess 45, so as to be flush with the face of the leg 10, as shown in Fig. 7, this pinion 44 being arranged to engage the rack 19, formed on the work-gage 18. It will be seen that by operating the handle 22 forwardly the work-gage, with its gage-finger 20, is likewise caused to be pushed forwardly to the extent desired; but the shaft 26 is clamped firmly enough in the block 27 to prevent the pressure of the work from reacting upon the gage sufficiently to move it back.

The hub 24 of the adjusting-handle is provided with a radially-projecting boss 46, from which proceeds a handle-arm 47 and which is adapted to coact with a tangential stop-screw 48, mounted in a transverse aperture in the pin 49, which is secured in an aperture in the end of the overhanging portion 28 of the work-head by a clamping-screw 50. The stop-screw 48 may be adjusted to limit the forward movement of the work-gage to any requisite extent, and it is provided with a lock-nut 51, which clamps it in the position to which it is set. It will be observed that the pinion 39 is made with a wider face than the gear-segment 32, so that while the latter is stationary the former in reciprocating shall always be in full intermeshing engagement with the said gear-segment, thus providing for the adjustment of the gage during the operation of the machine, while the adjusting-handle remains stationary.

It will be observed that at any time during the operation of the work the stationary handle 22 may be adjusted to regulate the distance of the seam from the edge of the leather, according as may be desired, without in any way interfering with the formation of the seam, and, in fact, the gage may be continuously adjusted as the work proceeds, so as to continuously vary the distance of the seam

from the edge of the work—an operation which has not been practically possible in any former type of machine.

While I have shown in the accompanying drawings the preferred form of my invention, it will be understood that I do not limit myself to the precise form shown, for many of the details may be changed in form or position without affecting the operativeness or utility of my invention, and I therefore reserve the right to make such modifications as are included within the foregoing description or the following claims.

Having thus described my invention, what I claim as new, and desire to secure by Letters Patent, is—

1. In a shoe and leather sewing machine, the combination of a work-gage slidably mounted in the feed-carriage, and means stationary during the operation of the machine for adjusting said gage, and an operative connection between said stationary adjusting means and said work-gage.

2. In a shoe and leather sewing machine, the combination of a reciprocating feed-carriage, a work-gage slidably mounted in said carriage, oscillating means mounted in said carriage for reciprocating said work-gage to adjust the distance of the seam from the edge of the work, and an adjusting-handle carried by the machine-frame and having operative connections with said oscillating means, whereby the work-gage may be adjusted.

3. In a shoe and leather sewing machine the combination of a laterally-reciprocating feed-carriage, a work-gage slidably mounted on said carriage and adapted to be operated backward and forward, a rack formed on one edge of said gage, a counter-shaft mounted in said carriage, a pinion mounted on one end of said counter-shaft, and engaging with said rack, a second pinion mounted on the other end thereof, an adjusting-shaft parallel to the motion of the carriage and mounted in stationary bearings, and a gear-segment carried by said adjusting-shaft and meshing with said second pinion whereby the reciprocation of said carriage does not interfere with the adjustment of the work-gage.

4. In a shoe and leather sewing machine, the combination of a laterally-reciprocating feed-carriage, a work-gage slidably mounted on said carriage and adapted to be operated backward and forward, a rack formed on one edge of said gage, a counter-shaft mounted in said carriage, a pinion mounted on one end of said counter-shaft and engaging with said rack, a second pinion mounted on the other end thereof, an adjusting-shaft parallel to the motion of the carriage and mounted in stationary bearings, a gear-segment carried by said adjusting-shaft and meshing with said second pinion, whereby the reciprocation of said carriage does not interfere with the adjustment of the work-gage, and an adjusting-handle mounted on the outer end of said adjusting-shaft.

5. In a shoe and leather sewing machine, the combination of a laterally-reciprocating feed-carriage, a work-gage slidably mounted on said carriage and adapted to be operated backward and forward, a rack formed on one side of said gage, a counter-shaft mounted in said carriage, a pinion mounted on one end of said counter-shaft and engaging with said rack, a second pinion mounted on the other end thereof, an adjusting-shaft parallel to the motion of the carriage and mounted in stationary bearings, a gear-segment carried by said adjusting-shaft and meshing with said second pinion, whereby the reciprocation of said carriage does not interfere with the adjustment of the work-gage, an adjusting-handle mounted on the outer end of said adjusting-shaft, said handle having a projecting boss and a projecting stop-screw adapted to coact with said boss to limit the motion of said handle.

6. In a shoe and leather sewing machine, the combination of a laterally-reciprocable feed-carriage, a work-gage slidably mounted to be adjusted backward and forward on the end of said carriage, an adjusting-handle mounted to turn in bearings, and connected with said work-gage to adjust the position thereof, and a bearing-block for said handle secured to the frame of the machine, and having one side slit so as to adapt the bearings to be more or less frictionally engaged with said adjusting-handle to keep the same from rotating.

7. In a shoe and leather sewing machine of the lockstitch type, the combination of a laterally-reciprocable feed-carriage having a depending leg, a work-gage slidably mounted in a recess in said depending leg and having a rack formed on one edge thereof, a pinion meshing with said rack, a short counter-shaft carried in said depending leg and carrying said pinion on the end thereof, a second pinion mounted on the other end of said shaft, and having a broadened face, an adjusting rock-shaft mounted in stationary bearings on the frame of the machine, and parallel to the motion of said carriage, a gear-segment mounted on the inner end of said last-named shaft and meshing with said second pinion, an adjusting-handle having a radial hub-boss clamped to the end of said rock-shaft, and a post mounted in the frame of the machine, and having an adjustable stop-screw adapted to strike against said hub-boss to limit the motion of said work-gage.

8. In a sewing-machine of the lockstitch type, the combination of a laterally-reciprocating carriage having a depending leg, a work-gage slidably mounted in a recess on said leg and adapted to reciprocate toward and from the front of the seam, a rack formed on the upper side of said work-gage, a pinion meshing with said rack, a short counter-shaft mounted to turn in said depending leg and having said pinion mounted thereon, a second pinion mounted on the other end of

said shaft and having a broadened face, a stationary bearing-block having an aperture therein, and a cut joining said aperture with the exterior of the block, clamping means for securing said block to the frame of the machine and for compressing said cut to increase the friction of said bearing-aperture, an adjusting-shaft mounted in said bearing-aperture parallel to the motion of said carriage, a gear-segment mounted on the inner end of said shaft and meshing with said second pinion and having a face of less width than the latter, an adjusting handle-arm fixed

upon the end of said adjusting-shaft and having a radial hub-boss, a projecting post secured in the frame of the machine, and a transverse adjustable set-screw mounted in said post and adapted to form a stop for limiting the forward motion of said hub-boss and the work-gage, substantially as described. 15 20

In witness whereof I have hereunto set my hand in the presence of two witnesses.

JOSEPH LOUIS KIEFFER.
